LAUNDRY MACHINE HAVING WASHING,
RINSING, AND LIQUID EXPELLING MEANS

Einer C. Olson, Milwaukee, Wis.

Application November 23, 1945, Serial No. 630,213

21 Claims. (Cl. 68—10)

1

My invention relates to improvements in laundry machines, with particular reference to machines of that type in which each patron's clothing is segregated in separate drums or baskets according to the character of the clothing and the requirements for cleansing it, and then advanced from a loading station step by step for successive washing and rinsing operations.

The primary objects of my invention are to provide practical means for avoiding contamination of the clothing of each patron from that of other patrons, and for interposing, between the last rinsing station and the unloading station, means for quickly expelling the watery content of the clothing and delivering it in sufficiently dry condition for immediate ironing.

Further objects are to provide for reducing the number of required operators by increasing the mechanical or automatic controls—to provide improved means whereby the water content of the tubs at each washing and rinsing station may be automatically replaced with pure water at the required temperature after each washing or rinsing operation—to provide improved means for returning the empty drums to the loading station; to provide for controlling the water expelling and drum returning operations without interference with the loading, washing and rinsing operations—and, in general, to provide reliable means for successively delivering cleansed and substantially dried family washes at intervals of about four or five minutes.

In the drawings:

Figure 1 is a side elevation of a laundry machine embodying my invention in its preferred form, with its driving connections and water supply pipes removed.

Figure 2 is a detail cross sectional view, showing one set of washing tubs and drums.

Figure 3 is a fragmentary plan view, enlarged, showing the driving connections of the spinner.

Figure 4 is an elevation of the unloading end of the machine, with parts broken away, as indicated.

Figure 5 is a plan view showing the driving connections, and with portions of the drum returning conveyor broken away.

Figure 6 is a sectional view taken on line 6—6 of Figure 5.

Figure 7 is a detail view, partly in elevation and partly in section, drawn to line 7—7 of Figure 5.

Figure 8 is a plan view of the tubs, crank wheels, water supply pipes, and tub outlets, with all other parts removed and portions of the tubs broken away.

2

Figure 9 is a view of the same, partly in side elevation and partly in section, taken on line 9—9 of Figure 8, showing also the means for opening the outlet valves.

Figure 10 is an enlarged detail side view of the valve mechanism of the water supply connections and associated parts.

Figure 11 is a fragmentary end elevation of the same.

Figure 12 is a plan view of the same, showing the supply pipes in cross section.

Figure 13 is a detail sectional view of one of the water inlet valves.

Figure 14 is an enlarged side elevation of a portion of a clothes drum returning mechanism and some of the associated parts.

Figure 15 is a front elevation of a set of washing drums.

Figure 16 is a similar view, showing the same drums mounted in spinner tubs, one of which is illustrated partially in section.

Figures 17 and 18 are sectional views drawn respectively on line 17—17 of Figure 15, and line 18—18 of Figure 16.

Like parts are identified by the same reference characters throughout the several views.

In its general organization, a series of sets of washing tubs, rinsing tubs, and one set of tub-like spinner receptacles are disposed along a line of washing drum advancement and corresponding sets of washing drums or baskets, each free for removal if desired, are advanced step by step from a filling and loading station, and successively assembled with each set of tubs in the tub series for washing, rinsing and spinning operations. Each set of drums is then advanced to an unloading station where their charges of clothing are removed, whereupon the empty set of drums is carried by a line of controlled conveyors to the filling or loading station to be refilled and the operation repeated. A sufficient number of drum sets is employed under the control of two operators, one at the loading station and the other at the unloading station, to enable a family wash to be delivered every few minutes as long as the supply of bundles of clothing can be maintained.

In the illustrated embodiment, a single elongated tank 20, mounted in a correspondingly elongated rectangular frame 21, is divided by longitudinal partitions 22 and cross partitions 23 into a row of tubs A for white clothing, a row of tubs B for light colored clothing, and a row of tubs C for dark clothing (Figures 2 and 7 to 12, inclusive). There will preferably be as many rows of tubs as there are kinds or classes of clothing to

be separately bundled and washed, but in the drawings only three rows of tubs are illustrated. The transverse dimensions of each tub will determine its relative capacity as compared with the tubs in the other rows, all of the tubs and tub-like receptacles being of the same depth and the same dimensions along lines extending longitudinally of the tank. The frame 21 is supported by posts 24.

Each row of water receiving tubs is supplied from below through a pipe 30a, 30b, and 30c, reduced in diameter under each tub as indicated at 31 in Figure 9, and immediately preceding each reduction it is connected with the associated tank by a vertical pipe 32, the reductions in diameter being calculated to progressively reduce the capacity of the pipe 30 from its receiving end so as to deliver equal quantities of water to each tub in the row. The pipes 30 under each row of tubs A, B and C are elbowed at 33 and respectively connected with vertical supply pipes 34, 35 and 36 at one side of the machine, as best shown in Figure 8. Each of these vertical pipes 34, 35 and 36 receive water at the proper temperature from a source of supply (not shown), and each is provided with a valve at 37 controlling deliveries to the supply pipes underneath the tank. Each valve 37 has a depending stem 40 which extends through the lower end wall of the vertical supply pipe, as best shown in Figure 13, whereby these valves may be closed by a cam 41 on a cam shaft 42. As cam 41 rotates, its high portion acts upon roller 43 to move arm 44 and rock the shaft 45 in a direction to lift arms 46 and raise the valve stems 40 and close the valves 37. When the low part of the cam 41 registers with roller 43, shaft 45 will rock in the opposite direction and the water pressure in the vertical pipes 34, 35 and 36 will push all of the valves 37 to open position to supply water to the water receiving tanks.

Each water receiving tub is also provided with a drain outlet having a valve 50, as best shown in Figures 8 and 9. These valves close by gravity and may all be simultaneously opened by a cam 51 on the cam shaft 42. This cam 51 bears on a roller 52 at the lower end of the lever 53 which is pivoted to the frame at 55, whereby the high part of the cam will cause the lever to swing to the left and transmit its motion through the link rod 56 to depending arms 57 on valve opening cross shafts 58. Said shafts have arms 59 which swing upwardly when the link rod is drawn to the left and operate all of the drain valves 50 through their depending stems 60, said upwardly swinging arms each registering with one of the drain valve stems. When the low part of the cam 51 is in registry with the roller 52, all of the drain valves will be permitted to close by gravity.

Liquid soap may be supplied to the washing tubs from a single source of supply through a suction pipe 64, (Figs. 8 and 9), pump 65, outlet pipe 66, and branches 66'. The piston 67 of the pump is actuated through an eccentric 68 on cross shaft 42' and the piston rod 69.

Every operation of the conveyor mechanism whereby the respective drums are advanced one step involves a complete rotation of the shafts 42 and 42'. Since the cams controlling the water and the soap are operated from the shafts, it will be apparent that in each operation the tubs are emptied and refilled.

The clothes containing drums and the means for advancing them step by step for successive operations will now be described. Each drum 75

is cylindrical in form and provided with a cover or door 76. In the construction shown, three drums compose a set, axially connected with each other at 78 and supported at each end by stud shafts 77, round in cross section except at one end, which are square in cross section, and adapted to be received in correspondingly shaped sockets of clutch members 80 carried by transmission shafts 81 (Figures 5 and 6).

The side members of the frame 21 are provided with open bearing members 85 in which the stud shafts of the several sets of drums may be received when the drums enter the tubs.

To periodically advance the sets of drums from one set of tubs to the next, I employ a set of lifting bars 90 (Figure 1), provided with open bearings or cradles 91 similar to the bearing members 85. These lifting bars are supported from crank pins 93 and 94 carried by crank wheels 95 and 95' on the cam shaft 42 and the parallel cross shaft 42', respectively. The crank pins 93 and 94 are connected with the lifting bars by V-shaped supporting arms 97, the divergent upper ends of which are secured to the lifting bars 90. In the construction shown, the crank wheels 95 are revolved counter-clockwise, and the cradles or saddles 91 on the lifting bars are so located that during the upper half of each crank wheel rotation these saddles will register with and engage all of the drum stud shafts in the open frame bearings 91, thereby lifting the drums and carrying them to the left.

As the crank pins descend, the lifting bars will deposit each set of drums in the open bearings 85 associated with the next set of tubs except the last set of the series, where the end set of drums will have their stud shafts deposited in the arcuate depressions 100 in the rear end portions of the frame bars to support the drums at the unloading station.

The crank wheels 95 on cam shaft 42 are driven by a motor 101 through the gearing 102-103, shaft 104, worm 105 and worm ring 106 on the periphery of the associated crank wheel 95. The crank wheels on the shaft 42', are driven by connecting link bars 107. The drums at the washing and rinsing stations are rotated by a periodically reversible motor 110, sprocket chains 111 and 112, and the transmission shafts 81 with their couplings 80 when in engagement with the stud shafts 77 of these drums.

At the water expelling station, each set of drums arriving at that station is converted into a spinner after being received in tub-like receptacles 115a, 115b and 115c, (Figure 5). Each of these receptacles is provided with an open drain port 116 (Fig. 8) and no water supply connections. To prevent water from being thrown from these receptacles during a spinning operation, each receptacle is provided with a cover 117, (Figures 16 and 18), which has end walls 118, each provided with an arcuate rib 119 mounted to slide in correspondingly curved grooves 120 in supporting plates 121 carried by the frame. Normally these covers occupy the depending position in which they are shown in Figures 16 and 18. They are connected by a handle 123 whereby they may be manually swung to a covering position over a set of clothes containing drums at the spinning station. When in this position, the arcuate portions 125 of the end walls 118 bear upon the upper surfaces of the stud shafts 77 and hold them in the open bearings 85' at this station, the ribs 119 being long enough to maintain their engage-

ment in the grooves 120 and prevent dislodgement of the covers.

At this station, each set of drums is revolved at an accelerating speed by an independent motor 130 (Fig. 5) which rotates the drum through a sprocket wheel on the transmission shaft 132, which has a square jawed coupling member 133 similar to the coupling members 80 associated with the washing and rinsing tubs. The drum spinning operation is completed in the same length of time required for each washing and rinsing operation, and the next operation of the lifting bars 90 will therefore advance the drums of one set from the spinning station to the unloading station and deposit them with their shafts supported in arcuate depressions 100 (Figure 1) in the side bars 21 of the frame, this being the unloading station.

After removing the contents from the drums of this set, the operator at the unloading station returns the unloaded drums to the vicinity of the loading station by means now to be described.

An endless drum returning conveyor comprises conveyor chains 140 at the respective sides of the machine in vertical planes which include the drum stud shafts, (Figures 4, 5, and 14). These chains are provided with hook-like shaft engaging prongs 141. At their forward ends, they are supported by sprocket wheels or pulleys on a shaft 142 and are driven from a motor 144 through suitable gearing and a sprocket chain 145 which runs over a sprocket wheel at 146 mounted on the shaft 142. At the rear end of the machine the chains run in channel bars 147 and downwardly to pulleys 149 so located that the hook-shaped prongs 141 will engage stud shafts in the frame depressions 100 to lift them and carry their associated drums to the front end of the conveyor, where the stud shafts of this set of drums are delivered to prongs 155 on a vertical conveyor 156 having its chains mounted to run over sprocket wheels 157 and 158 at the respective sides of the machine. Simultaneously with the delivery of one set of drums to this vertical conveyor, the drums strike a switch lever 160 which opens the circuit of the motor 144 and arrests the movement of chains 140. The switch 160 is spring actuated and automatically closes when the pressure of the contacting drum is relieved.

The conveyor operates by gravity under the weight of an engaged set of drums to lower the drums to the loading station under the control of a brake 165 having a lever 166 normally locked in brake setting position to prevent movement of the conveyor 156 pending a release of the lever 166 by the operator at the loading station, who withdraws latch 170 from the notched sector 171 in which it is normally locked, and releases the brake, as soon as the lifting bars 90 have advanced a previously loaded set of drums from the loading station to the first washing station. He then resets the brake 165, pending delivery to conveyor 156 of another set of empty drums by conveyor 140.

By automatically regulating the supply of water to each washing and rinsing tub so that each tub receives an equal depth of water in the limited time that the supply controlling valves are open, and by likewise regulating the supply of liquid soap to the washing tubs and by using rotary drums instead of oscillatory drums or baskets, I avoid the waste which has heretofore been regarded as requiring the use

of the same water and soap for successive family washings.

Rotary drums, equipped with clothes lifting ledges 175, (Figure 17), require no great depth of water in the tubs for the reason that the rotation of the drum lifts the clothing above the water and drops it into the water with considerable gravity impact, and a reversal of the direction of rotation causes a rearrangement of the clothing so that all portions are subjected to impacts during the washing operations. By automatically opening and closing the valves, the tubs can be emptied and refilled without requiring any attention on the part of the operator.

At the loading station the operator is merely required to release and reset the brake controlling delivery of a drum to that station and then load the clothing in the proper drums. At the unloading station the operator has three duties, viz.—to operate the handle 123 to cover and uncover the drums at the spinning station—to unload the drums at the unloading station—and to operate the switch to start the motor and return conveyor.

Therefore only two operators are required to wash and deliver complete family washes in a substantially dry condition at regular intervals of about four or five minutes.

Every time the motor 101 is operated to rotate the shafts 42, 42' 360°, the conveyor frame 90 connected with the crank pins 93, 94 of the wheels 95, 95' has an orbital movement whereby the several cradles 91 lift the respective shafts 77 and the drums mounted thereon, transport the shafts 35 and drums one station in advance, and deposit them in the bearing troughs 85 of the respective tubs. At the commencement of the operation, the tubs are drained and in the course of the transporting operation, they are refilled as above 40 described. Accordingly, when the shafts 77 are engaged by the driving chucks 80 at the new station, the drums will be rotated in fresh water by power derived from motor 110. Since each such shaft carries several drums holding the different types of clothing of a single family wash, 45 and since each type of clothing is washed separately in the corresponding tubs in which the several drums are disposed, the color or soil from one type of clothing will not affect clothing of other types, despite the fact that all of the clothing of a given family wash is handled unitarily. After the drums on a given shaft have moved from station to station through the entire series of washing and rinsing operations, the 50 drums and their contents will be centrifuged by high speed rotation at a drying station where the shaft will be engaged by the chuck 133 driven by an independent motor 130. The centrifuging is accomplished during the same dwell of the 55 movement of the conveyor frame which provides time for the washing and rinsing operations.

On the next succeeding conveyor frame movement, the shafts carrying the drums whose contents have been centrifuged are deposited at the 60 unloading station 100 where an operator in charge of the motors above-described removes the clothes from the several drums on the shaft at such station. He then energizes motor 144 which actuates the overhead return conveyor for lifting the shaft and the empty drums and returning them toward the loading station. The shaft bearing the empty drums is deposited onto the gravity-operated vertical conveyor 156 where it engages a switch, deenergizing the motor 144. Conveyor 156 is held stationary by the brake 166.

until the operator at the loading station is ready to receive the empty drums. The brake being released, the empty drums descend on conveyor 156. Either in their lowered position or at some intermediate position, the empty drums are loaded with another wash and when the shaft carrying them is finally deposited in the path of the conveyor frame, the sequence of operations above described is repeated.

It will, of course, be understood that the cross shafts 42 and 42' have crank lifting bars at each side of the machine, and if desired, all of the tubs may be provided with covers 117 like those used at the water expelling station.

I claim:

1. In a laundry machine having loading, washing, rinsing, water-expelling, and unloading stations, the combination of a series of enclosed perforated clothes containers having shaft means for their respective rotatable support, means for periodically advancing said containers, step by step, from said loading station to said washing, rinsing, water-expelling and unloading stations, liquid receptacles at said washing and rinsing station, a constantly drained receptacle at the water-expelling station, said advancing means comprising means for depositing said containers in said receptacles in the intervals between their step by step advancement, means for rotating the containers in the liquid receptacles, the said receptacles having bearings for the shaft means of said container, and means for revolving each container deposited at the water-expelling station at a speed sufficient to expel its water content by centrifugal force.

2. A laundry machine as set forth in claim 1, provided with separate manually controlled means for returning said containers from the unloading station to the loading station.

3. A laundry machine as set forth in claim 1, provided with means for automatically draining the washing and rinsing receptacles and supplying them with fresh water concurrently with each advance of the clothes containers.

4. A washing machine provided with parallel rows of sets of transversely aligned tubs, in combination with sets of perforate drums having work receiving openings and provided with supporting means on which they are movable from one set of tubs to another, means for effecting the step by step advance of the drums upon said supporting means from one tub to another, means for draining some of the sets of tubs and supplying them with fresh water concurrently with each drum advance, power driven means for advancing the drums periodically and rotating them in the respective tubs in the intervals between their advancing movements, and separate, manually controlled power driven means for rotating each set of drums at a water expelling speed at one stage of its advancement.

5. In a laundry machine, loading, washing and rinsing stations, a series of perforated clothes containers and means for moving them step by step to and beyond said washing and rinsing stations, and returning them successively to said loading station, housing means for enclosing said containers at one stage of their step by step advancement, and manually controlled means for rotating each container at high speed in said housing means.

6. In a laundry machine having a series of sets of tubs providing washing and rinsing stations, and sets of drums having work receiving doors and water admitting openings, each drum set

being provided with axially disposed stud shafts common to the drums of the set and adapted for coupling engagement with transmission shaft connections associated with said tubs at the respective stations, the combination therewith of supporting means engaging said stud shafts and upon which the drums are movable power driven means for advancing said drum sets step by step and coupling their shafts with said transmission shaft connections at the respective stations, said power driven means also controlling the admission and exhaust of water from the tubs before and after each washing and rinsing operation, means for revolving said drums at slow speeds at the washing and rinsing stations and at extracting speeds after leaving said stations, and manually operable means for housing said drums while they are revolved at the extracting speeds.

7. In the combination set forth in claim 6, means for delivering each drum to an unloading station after expelling its water content by extraction, and manually controlled means for returning unloaded drums to a loading station preparatory to another advance through the washing and rinsing stations.

8. In a laundry machine, loading, washing, rinsing and unloading stations, perforated rotary drums and means for advancing said rotary drums from one station to another and rotating them at the washing and rinsing stations, return conveyor means for moving empty drums from the unloading station to the vicinity of the loading station, an electric motor for operating the return conveyor means, a switch for opening the circuit of the motor, said switch being operable by the returning drum to stop said motor, and manually operable means including control means at the loading station for controlling delivery of an empty drum thereto after it has stopped said motor.

9. In a laundry machine having a series of loading, washing, rinsing, water expelling, and unloading stations, and a series of perforated clothes containing drums movable step by step from one station to another for loading, washing, rinsing, water expelling and unloading operations, in combination with a motor driven return conveyor for moving unloaded drums from the unloading station to a point above the level of the loading station, a gravity actuated conveyor for receiving the returned drums and depositing them at the loading station, a brake for controlling movements of the gravity actuated conveyor, and a drum actuated switch for stopping the drum returning conveyor upon delivery of an empty drum to the gravity actuated conveyor.

10. A laundry machine organized for continuous movement of a series of clothes containers from a loading station through a series of servicing stations and unloading station, the combination therewith of a conveyor for returning drums to the vicinity of the loading station, a motor for driving the drum returning conveyor, a manually operable switch for starting said motor, a switch operable by a returning drum for automatically opening the motor circuit to stop said motor, and manually controlled means at the loading station for delivering a drum from its switch operating position to said loading station.

11. A laundry machine comprising a series of tubs and a frame for said tubs provided with open bearings at stations respectively corresponding to the tubs, a foraminous drum provided with shaft means rotatable in the respective bearings, a conveyor frame having shaft re-

ceiving saddles and operating cranks connected with said conveyor frame for the orbital movement thereof on a path such that each saddle is adapted to pass one of said bearings in its upward movement and a different bearing in its downward movement, a source of power in operative connection with said cranks for the actuation of said conveyor frame, said cranks comprising movable supports for the conveyor frame, and a driver engageable with said shaft means at one of said stations for the rotation of said shaft and drum in the tub at such station.

12. The combination set forth in claim 11 in further combination with means operated from said power source for draining the water from and admitting water to said tub, and driving connections to said driver including speed reducing mechanism whereby said driver is adapted to actuate said shaft means and drum at washing speeds.

13. The combination set forth in claim 11 in further combination with driving connections to said driver including speed reducing mechanism for actuating said driver to actuate said shaft means and drum at washing speeds, and a separate driver and separate driving connections thereto at another station, said last mentioned connections and driver being operable to actuate the shaft means and driver at extracting speeds.

14. A laundry machine comprising a series of open bearings at successive washing, rinsing and extracting stations at substantially uniform spacing throughout the series, tubs at some of said stations, a driving chuck at the extracting station and power operating connections to drive said chuck at extracting speeds, a driving chuck at the washing station, and connections whereby said last mentioned chuck is driven at washing speeds, a foraminous drum having supporting shaft means engageable in the bearings aforesaid and operable by the respective chucks, and conveyor means for advancing said drum and shaft means from station to station.

15. The combination set forth in claim 14 in which said conveyor means comprises cranks paired at opposite sides of the tubs and a conveyor frame having shaft engaging cradles paired at opposite sides of the tubs at a spacing corresponding to the spacing between said bearings, said conveyor frame being operatively connected with said cranks for orbital movement upon a path such that each pair of said cradles moves upwardly past the bearings at one station and downwardly past the bearings at another station, thereby lifting said drum and shaft means from one tub and its associated bearings and depositing said shaft means in the bearings at another station.

16. In a laundry machine having fixed stations at which selected laundry operations are performed, the combination with a main frame extending at each side of the stations and provided with pairs of oppositely disposed open bearings substantially uniformly spaced at successive stations, of a conveyor frame having pairs of cradles correspondingly spaced and having crank means mounting the conveyor frame for orbital movement from a level below the main frame to a level thereabove and return, said cradles passing positions of alignment with one of said pairs of bearings in the course of their upward movement and positions of alignment with the pairs of bearings of another station in the course of downward movement of said conveyor frame, and a foraminous drum having shaft means en-

gageable in the bearings and cradles and adapted to be advanced by conveyor operation from one station to another.

17. The combination set forth in claim 16 in further combination with a driving chuck at one of said stations having an upwardly opening channel registering with the bearings thereat, said shaft means being receivable into said channel and said chuck being provided with driving connections for the actuation of said drum with its shaft means received in the channel of said chuck.

18. The combination set forth in claim 16 in further combination with driving chucks at a plurality of said stations, a low speed driving connection to one of said chucks, a high speed driving connection to a chuck at a subsequent station, and a tub at the station served by the low speed chuck and positioned to support a liquid in which said foraminous drum will be engaged at said last mentioned station.

19. The combination set forth in claim 18 in which said main frame is provided at the station served by the chuck having high speed driving connections with a cover movable for the admission and discharge of said drum and positioned normally to enclose a drum at said station to confine liquid extracted from the contents of said drum.

20. A laundry machine comprising the combination with a plurality of foraminous drums each provided with oppositely projecting shaft means, of a machine frame provided at successive uniformly spaced initial, final and intermediate stations at which selected laundry operations are performed with pairs of oppositely disposed recesses in which said shaft means are engageable, a conveyor comprising an orbitally movable sub-frame, pairs of cradles carried by said frame spaced correspondingly to said recesses and adapted in the course of orbital movement to lift said shaft means from one of said pairs of recesses to another, cranks connected with said sub-frame for imparting orbital movement thereto upon a path such that the cradles of the sub-frame pass a position of alignment with one station in the upward movement of the sub-frame and a position of alignment with another station in the downward movement thereof, a liquid-retaining tub at one of said stations for wetting the contents of the drum at said station, a chuck at said last mentioned station in alignment with the recess thereof and comprising shaft engaging means for the rotation of a drum at said last mentioned station, driving connections for said chuck adapted to rotate it at washing speeds, a second chuck at a subsequent station engageable with the shaft means of a drum at said last mentioned station and provided with driving connections for operation of the drum at extracting speeds, an overhead conveyor having shaft engaging means and arranged to lift drums and their respective shaft means from the final station on said machine frame and return said drum and shaft means to a position over the initial station on said machine frame, and means including a lowering elevator with drum shaft receiving portions for delivery of a drum and shaft means from said overhead conveyor to said initial station.

21. In a laundry machine having a series of washing and rinsing stations, tubs at said stations, a plurality of perforate work containers having shaft means for their rotatable support, bearing means on said tubs with which said shaft means are rotatably engageable, a conveyor

system comprising means for the support and step by step advance of said containers from the bearing means of one tub to the bearing means of a successive tube, driving means engageable with successive containers at certain of said tubs for the rotation of said containers at washing and rinsing stations, bearing means on said tubs beyond said washing and rinsing stations with which the shaft means of said containers are engageable, said conveyor means being adapted to progressively advance the containers to said last mentioned bearing means, and driving connections for rotating containers at a water expelling speed when their shaft means are engaged with said last mentioned bearing means.

EINER C. OLSON.
